DONALD G. LITTLE, OF EDGEWOOD, PENNSYLVANIA, ASSIGNOR TO WESTINGHOUSE ELECTRIC & MANUFACTURING COMPANY, A CORPORATION OF PENNSYLVANIA

CONDENSER

Application filed October 22, 1926. Serial No. 143,400.

This invention relates to radio systems and particularly to transmitting systems in which the antenna is located out-of-doors and the connection between it and the transmitting mechanism is reactive.

It is an object of this invention to produce an antenna connection which shall be unaffected by the weather.

It is a further object of this invention to prevent falling rain-drops from causing noises in the receiving sets in which the signals from said transmitting system are received.

In many transmitting systems now in use, it is customary to insert a condenser in the connection between the antenna and the remainder of the transmitting set. Frequently, when the antenna is out-of-doors and the rest of the transmitting mechanism is inside a building, the condenser has been formed of two vertical closely adjacent plates outside the building. It has been found that falling rain-drops passing between the condenser plates cause disturbances which appear as noises superposed upon the music or other signal transmitted.

I have avoided such disturbances by substituting for the condenser composed of two plates, a condenser composed of a bell-shaped member and an upstanding member within the bell.

My invention will be better understood and further objects therof perceived from the following description and the accompanying drawing, in which:

Fig. 1 is a view, in elevation, of an antenna embodying my invention,

Fig. 2 is a detail, partly in section, of the condenser, and

Fig. 3 is a similar detail of a modification of one member of the condenser.

The mast 1 supports the vertical rigid antenna 2 having an inductance coil 3 near the middle thereof and an adjustable connection 4 between said coil and the lower half of

the antenna. At the bottom of the antenna a horizontal pipe 5 constitutes the lower capacity element. One end of the pipe 5 is turned upwardly, as shown at 6 in Fig. 2, and is inside of a bell-shape conducting member 7. The bell-shape member 7 and the pipe 5 are supported upon suitable insulating supports 8.

The proper relative position between the end 6 and the bell 7 is secured by a bracket 11. Any suitable provision for adjustment of the relative position of the end 6 and the bell 7 may be made at the junction of the insulators and the bracket or of the insulators and the conductors supported thereby. A connection 12 extends from the bell 7 to the transmitting mechanism. The connection between conductor 12 and the bell 7 may be afforded by a lug 13 or any similar device.

The upper end of the upturned part 6 is rounded, as shown at 14, to avoid sharp edges. The top of the bell-shaped member is dome-shaped to correspond to the rounded end 14, in order that the space between the upstanding end 6 and the bell may be of uniform thickness throughout. The edge 15 of the bell is flared outwardly, in order to provide a more gradual diminution of the field between the bell and the pipe and also to afford eaves from which rain-water may drip without disturbing the distribution of the electric field.

Preferably, the edge of the bell slopes, being highest over the horizontal part of the pipe and lowest at the opposite side. This shape will ensure that, as water drips from the bell, it will not pass near the pipe.

The bell 7 may be made of sheet metal, as shown in Fig. 3. In this form, the rounded edge is provided by a rolled flange 16. At the point farthest from the pipe 5, the flange 16 is turned down, as shown at 17, to provide a spout from which the rain-water will drip without disturbing the field around the pipe.

In the operation of the device, energy is

received along the conductor 12 and delivered to the pipe 5 by the condenser action between the bell 7 and the upturned end 6 of the pipe 5. The electric field established between the electrodes 6 and 7 is of substantially uniform distribution. Moreover, when it rains, no water-drops enter this field because it is sheltered by the bell-shape of the electrode 7. The dielectric constant of the material in the dielectric space remains unaltered, therefore, even during a rainstorm, and abrupt changes in the capacity of the condenser cannot be caused by such rain-drops. The noises caused by raindrops in the apparatus heretofore used are thereby avoided.

The rain which falls upon the outside of the bell 7 is without effect upon the field inside. Moreover, when the rain collects on the eaves 15 in the form of drops, the change in the shape of the electrode 7, caused by the collected drops, is almost completely without effect upon the capacity because the drops are at a greater distance from the pipe 5 than is most of the bell.

As rain-drops fall from the low point of the edge 15 or from the end of the spout 17, they pass through a path that is well outside the electric field of the pipe 5 and are without effect upon the signals.

While I have shown and described only two particular forms of my invention, changes may be effected therein without departing from the spirit and scope thereof, as set forth in the appended claims.

I claim as my invention:

1. In a radio system, an antenna comprising an upright part and a lower part at an angle thereto, a connection to said antenna comprising a condenser, one element of which is the upturned end of said lower part.

2. In a radio system, an antenna comprising an upright part and a lower part at an angle thereto, a connection to said antenna comprising a condenser, one element of which is of bell shape and another element of which is the upturned end of said lower part, said lower part being housed within said bell-shape part, whereby rain-drops are excluded from the dielectric space of said condenser.

3. In combination, an antenna structure comprising a horizontal portion, said horizontal portion having an L-shape terminal providing an upright part, and a bell-shape metallic element so disposed with respect to the upright part of said terminal as to constitute a coupling condenser therewith.

4. In combination, an antenna structure comprising a rigid horizontal portion, said horizontal portion having an L-shape terminal, a bell-shape metallic element having a flanged lip, and means for rigidly supporting the upright part of said terminal within said bell-shape element to thereby constitute a coupling condenser.

5. In combination, an antenna structure

comprising a rigid horizontal portion, said horizontal portion having an L-shape terminal, a bell-shape metallic element having a flanged lip, one portion of said flange being turned down to provide a drip-spout, and means for rigidly supporting the upright portion of said terminal within said bell-shape element to constitute a coupling condenser, said spout being directed away from the horizontal portion of said terminal.

In testimony whereof, I have hereunto subscribed my name this 19th day of October, 1926.

DONALD G. LITTLE.
